UNITED STATES PATENT OFFICE.

LEOPOLD DE VOS AND ANTON F. SANDERS, OF MINNEOTA, MINNESOTA.

GRAIN-SEPARATOR.

1,083,437.

Specification of Letters Patent.

Patented Jan. 6, 1914.

Application filed July 17, 1913. Serial No. 779,577.

To all whom it may concern:

Be it known that we, LEOPOLD DE VOS and ANTON F. SANDERS, citizens of the United States, residing at Minneota, in the county 5 of Lyon and State of Minnesota, have invented certain new and useful Improvements in Grain-Separators; and we do declare the following to be a full, clear, and exact description of the invention, such as will enable others skilled in the art to which it appertains to make and use the same.

This invention relates to improvements in grain separators and particularly to means for separating wild oats from cultivated oats 15 and other grain.

One object of the invention is to provide a machine of this character having an improved construction and arrangement of separating mechanism and improved means 20 for removing the wild oats from the separating apron of the machine without injuring the apron.

A further object is to improve the separator shown in United States Patent No. 25 1,053,791 granted to us February 18, 1913 whereby this machine is rendered more efficient in operation.

With these and other objects in view, the invention consists of certain novel features 30 of construction, and the combination and arrangement of parts as will be more fully described and claimed.

In the accompanying drawings: Figure 1 is a side view of one side of our improved 35 grain separator; Fig. 2 is a similar view of the opposite side; Fig. 3 is a front end view; Fig. 4 is a rear end view; Fig. 5 is a central vertical longitudinal section of the machine; Fig. 6 is a similar view taken on the line 40 6—6 of Fig. 3; Fig. 7 is a top plan view of the machine with the feed hopper removed; Fig. 8 is a perspective view of the agitating frame for the separating apron.

Our improved grain separator comprises 45 an apron supporting frame 1 consisting of parallel side bars 2 connected at their lower ends by a cross bar 3 which rests on the floor and supports this end of the frame. The opposite or upper ends of the frame 1 are 50 secured to the upper ends of standards 4 which support the frame 1 at the proper inclination. The frame 1 is further connected to the standards 4 at their lower ends by inclined brace bars 5 the upper ends of which 55 project above the side bars 2 for a purpose hereinafter described. The side bars 2 of

the frame 1 are connected intermediate their ends by cross bars 6 to which is secured an inclined platform 7 which supports the upper stretch of the separating apron hereinafter described thus preventing this stretch of the apron from sagging or becoming uneven.

Revolutely mounted in suitable bearings on the upper ends of the standards 4 is an upper apron supporting and operating roller 8 a lower apron supporting roller 9 being revolutely mounted in suitable bearings on the inner sides of the side bars 2 near the lower end thereof as shown. Engaged with the rollers 8 and 9 and adapted to travel around the platform 7 is an endless separating apron 10 which is constructed of fabric having a nappy surface to which bearded grain such as wild oats will adhere. Fixed on one 75 end of the shaft of the upper apron supporting and operating roller 8 is a sprocket gear 11 which is connected by a sprocket chain 12 to a sprocket gear 13 on the adjacent end of a main guide shaft 14 which is revolutely 80 mounted in suitable bearings arranged on bearing bars 15 which connect the standards 4 with the sides 2 of the apron supporting frame. On the opposite end of the main drive shaft 14 is a combined crank wheel 85 and pulley 16 having a crank handle 17 whereby the same and the shaft 14 are revolved to move the apron 10 in the proper direction.

Secured to the side bars 2 of the frame 1 and projecting above the same is a hopper supporting frame 18 in which is arranged a feed hopper 19 having an inclined bottom 20 and a rear side 21 which is adjustable to space the lower edge thereof a greater or less 90 distance from the lower edge of the bottom whereby the width of the discharge opening in the bottom of the hopper is regulated to permit the grain to feed more or less rapidly 95 from the hopper.

Loosely supported on the hopper frame 18 by links or hangers 22 is a grain separating shoe 23 comprising an upper inclined plate 24 and a lower inclined plate 25. The plates 24 and 25 are spaced a suitable 105 distance apart and secured at their ends to triangular end pieces having their apices disposed at the front end of the shoe whereby the upper plate inclines forwardly toward the lower plate and terminates at its 110 lower edge a short distance from the adjacent front edge of the lower plate and forms

a discharge space through which the grain passes from the upper plate onto the lower plate 25 which inclines rearwardly toward the separating apron and from which the 5 grain is evenly distributed and discharged onto the separating apron. Secured to the lower cross bar at the front end of the shoe is a transversely disposed inclined tailings trough 26 which extends across the machine 10 and is designed to receive the tailings and coarse material which are caught by a screen 27 arranged on the shoe and spaced a suitable distance above the upper plate 24 thereof and onto which the grain falls when 15 discharged from the hopper. The grain passing through the screen falls onto the upper plate 24 of the shoe and slides down the same onto the lower plate and from this plate is discharged onto the separator apron 20 as hereinbefore described.

The shoe 23 and screen 27 are agitated or kept continually in motion by a suitable shaking mechanism which preferably comprises a bell crank lever 28 which is pivoted 25 on a bracket 29 secured to one of the side bars of the apron supporting frame as shown. One end of the bell crank lever 28 has a pivotal connection with the rear cross bar 30 of the shoe 23 while the other arm 30 of the lever is loosely connected by a link or operating rod 31 the forward end of which is loosely connected with a wrist pin 32 which is arranged eccentrically on the driving pulley 33 of a blast fan hereinafter 35 described, said pulley 33 being connected by a belt 34 with the main driving pulley 16 hereinbefore described. The crank action of the wrist pin 32 will rock or oscillate the bell crank lever 28 which in turn 40 will shake or agitate the shoe 23 thus keeping the grain thereon in motion and causing the grain to pass down the upper and lower plates and screen thereof as will be readily understood.

45 Arranged on the rear cross bar 30 of the shoe are a series of grain agitating loops 35 which project upwardly through the discharge opening of the hopper and which are agitated by the movement of the shoe and 50 thus prevent the grain in the hopper from becoming packed and choking or clogging the discharge opening thereof.

Mounted on the apron supporting frame 1 is a fan casing 36 the discharge opening 55 of which is disposed immediately below the rear edge of the lower plate of the shoe so that the air blast created by the fan 37 which is revolubly mounted in said casing will be discharged upon the grain as the 60 latter falls from said lower plate 25 onto the separating apron, thus blowing out or removing the chaff and light particles of foreign matter from the grain. The fan 37 is fixed on an operating shaft 38 revolubly 65 mounted in the ends of the fan casing and

on one end of each is fixed the drive pulley 33 hereinbefore described.

Arranged between the lower ends of the side bars 2 of the apron supporting frame is a lower grain separating shoe comprising 70 a frame 39 on which is arranged a screen 40 and which is loosely supported near its forward end by short links or hangers 41 which are connected to the inner side of the side bars 2. At its rear end the frame 39 is connected by links 42 to the lower ends of short agitating levers 43 which are pivoted midway between their ends to the inner sides of the side bars 2. The levers 43 are pivotally connected at 75 their lower ends to the right angular inwardly extending lower ends of pitman rods 44 the upper ends of one of which is loosely connected with the wrist pin 32 on the pulley 33. The pitman rod 44 on the opposite side of the machine is connected at 80 its upper end to a wrist pin 45 eccentrically arranged on a beater operating pulley 46 which is fixed on this end of the fan shaft and is thereby operated. By thus connecting the frame 39 of the lower shoe with the pulleys 33 and 46 on the fan shaft said shoe will be agitated so that the grain discharged onto the screen 40 from the lower 85 end of the apron will be finally cleaned and thoroughly separated from imperfect or inferior grain which will pass through the screen while the perfect grain will be discharged from the lower edge of the screen and may be caught by a conveyer or any 90 suitable receptacle provided to receive the same.

Arranged over the platform of the separating apron and below the upper stretch of the latter is an apron agitating frame 105 comprising side bars 47 which are connected near their upper and lower ends by cross rods 48, said rods being designed to strike against the inner faces of the upper stretch of the apron as the latter passes 110 along over the platform thereby agitating or shaking the upper stretch of the apron and keeping the grain thereon in motion. The side bars of the agitating frame are pivotally connected near their lower ends to the upper ends of the short agitating levers 43 while said side bars 47 are connected at their upper ends by links 49 with supporting blocks 50 having therein longitudinal slots 51 which receive clamping bolts 52 arranged in brackets 53 secured to the upper ends of the side bars 2 of the apron supporting frame as shown. By sliding the blocks 50 upwardly or downwardly on the clamping bolts 52 the inclination of 115 the links 49 and levers 43 is correspondingly varied and the apron agitating frame will be raised or lowered thus bringing the same nearer to or farther from the upper stretch 120 of the apron which will cause said frame 125 130

to agitate said upper stretch of the apron to a greater or less extent as will be readily understood. The bolts 52 are provided on their outer ends with clamping nuts 54 which when tightened up hold the blocks 50 in their adjusted positions for supporting the agitator frame at the desired elevation. By connecting the lower end of the agitating frame with the agitating levers 43 it will be seen that when said levers are rocked by the pitman rods 44, that the cross rods of the agitating frame will be brought into and out of forcible engagement with the upper stretch of the apron, thus keeping the latter agitated and the grain thereon in motion.

The grain when discharged onto the apron in the manner described is carried downwardly thereby and all except the wild oats and bearded grain is discharged at the lower end of the apron onto the screen 40 of the lower separating shoe. The wild oats and other bearded grain will adhere to the rough surface of the conveyer apron and will be thereby carried around and back up on the lower stretch of the apron from the surface of which the bearded grain hangs down and is supported by the bearded ends thereof which have obtained a firm attachment with the roughened surface of the apron. In order to remove the bearded grain which has thus become attached to the apron we provide a rotary beater 55 comprising a supporting shaft 56 on which are fixed radially projecting arms 57 which are connected at their ends by beater bars 58. The bars 58 are secured to the ends of the arms 57 at a suitable angle for engaging and knocking the wild oats and other bearded grain from the lower stretch of the apron as the grain is brought around in position to be engaged by the beater.

The shaft 56 of the beater is revolvably mounted in suitable bearing bars 59 connected to the standards 4 and side bars 2 of the apron frame and on one end of the shaft 56 is fixed a small pulley 60 which is connected by a belt to the beater operating

pulley 46 fixed on the adjacent end of the fan shaft as hereinbefore described. By thus connecting the beater with the fan shaft the movement of the latter will be imparted to the beater to revolve the same in the proper direction for removing the wild oats from the apron in the manner described and without injuring the latter.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described our invention, what we claim is:

A grain separator comprising a supporting frame, a separating apron operatively mounted therein, an apron agitating frame comprising side bars, rods connecting said bars and adapted to be brought into forcible engagement with the lower face of the upper stretch of the apron, levers pivotally connected to the apron supporting frame and having a pivotal connection at their upper ends with the side bars of said apron agitating frame, longitudinally slotted supporting blocks having an adjustable connection with said supporting frame, links connecting the upper ends of the apron agitating frame with said blocks whereby the upper end of the frame is adjustably supported with respect to the upper stretch of the apron.

In testimony whereof we have hereunto set our hands in presence of two subscribing witnesses.

LEOPOLD DE VOS.
ANTON F. SANDERS.
